(57) **CLAIM**

The ornamental design for fluid distribution equipment, as shown and described.

DESCRIPTION

FIG. 1 is a top plan view of a first embodiment of fluid distribution equipment in accordance with my design; FIG. 2 is a top, front, left perspective view thereof; FIG. 3 is a bottom view thereof; FIG. 4 is a bottom, front, left perspective view thereof; FIG. 5 is a right side elevational view thereof; FIG. 6 is a left side elevational view thereof; FIG. 7 is a rear elevational view thereof; and, FIG. 8 is a front elevational view thereof.

The broken lines represent portions of the fluid distribution equipment that form no part of the claimed design.
